UNITED STATES PATENT OFFICE.

HARRY T. SHEARER, OF WAYNESBORO, PENNSYLVANIA, ASSIGNOR TO LANDIS MACHINE COMPANY, OF WAYNESBORO, PENNSYLVANIA, A CORPORATION OF PENNSYLVANIA.

DIE HEAD.

Application filed November 11 1924. Serial No. 749,222.

My said invention relates to a die head intended primarily for use with automatic machines for cutting screw threads on pipes, rods and the like. In the case of such automatic machines the cams for closing the heads must be made or adjusted very accurately to insure proper closing action and where this is not done the locking elements of the die heads are often broken off or damaged. With the improved die head of my said invention such accurate positioning of the closing cams is not necessary thus increasing the life of the head and requiring less supervision. The same considerations apply to hand machines where the head is closed otherwise than by direct manual actuation; i. e., by mechanical or power-operated means.

Referring to the accompanying drawings, which are made a part hereof and on which similar reference characters indicate similar parts,

Figure 1 is a side elevation of an overtravel die head adapted to cut right-hand threads only,

Figure 2, a fragmentary longitudinal section of the same.

Figure 3, an end elevation,

Figure 4, a side elevation of a die head for cutting either right-hand or left-hand threads,

Figure 5, a fragmentary longitudinal section of the same, and

Figure 6, an end elevation thereof.

In Figures 1 to 3 of the drawings reference character 10 indicates a shank of conventional character on which the die head is supported. The die head is generally similar to that shown in applications 580, 40 210, August 7, 1922, and 581,160, August 11, 1922, by Samuel F. Newman and James G. Harper consisting of a series of rings 11, 12, 13 and 14 providing a ring frame surrounding the head body (not shown). The front 45 ring 14 is adapted to be moved by a handle 15 in a direction to move the cutter-carrying blocks with their trunnions 16 and thus bring the cutters 17, which are of the well-known "long-life" Landis type of adjustable tangential thread-cutters, into engagement with the work indicated at 18, it being understood that the cutter carrying blocks

are pivoted to the ring 14 at 19 as in the applications above referred to.

A spring 20 bears at one end against a 55 pin 21 fixed to the ring 14 for moving it in a direction to open the head and at the other end rests in a socket in a screw plug 22 which screw plug serves to adjust the tension of the spring. 60

A series of pins 23 are mounted for movement in a direction parallel to the axis of the head and have reduced portions 24 at their forward ends for engagement in hardened bushings 25 in the ring 14. These bushings 65 are located in apertures in the ring parallel to the axis of the head and internally threaded bushings 26 are located underneath the bushings 25 so that a threaded tool can be inserted into the opening and be turned to 70 effect secure engagement with the bushing 26 after which both bushings may be forcibly removed as explained in application 581,160, above referred to. The reduced end 75 24 of each pin 23 fits closely in its hardened bushing 25 and the ring 14 must be accurately positioned relatively to the ring 13 and other parts of the head if the pin 23 is to move directly into alignment with the bore of the bushing. Because of variations 80 in the position of the cams for closing the heads it is sometimes difficult or impossible in automatic and power-actuated machines to secure such accurate registration of the pin and the bore and therefore I have provided a recess at 27 cut back from the recess 85 in which the bushing 25 is located and have also cut away the bushing at one side.

The effect of the above change is that the closing cams on an automatic machine can 90 be set so that they force the ring 14 further in a counter-clockwise direction (Fig. 3) than is necessary for bringing the pins 23 into registration with the bores of their respective bushings 25. The ends 24 of the 95 pins are then free to slide into the depressions 27 and when the ring 14 is released by its closing cam the spring 20 immediately forces it into the position illustrated in Figure 2, when the chasers 17 will be in correct 100 position for operation.

In Figures 4, 5 and 6 the shank and the rings 11, 12 and 13 are as hereinbefore described. The ring 14, however, is modified

to permit the head to be locked in position for cutting either right-hand or left-hand threads. For this purpose the ring is provided with pairs of recesses in which are located twin bushings 28 beneath which are internally threaded twin bushings 29. The bushings 28 are cut away at their adjacent sides as indicated at 30 to permit the pins 23 to assume their locking position on over-travel of the ring 14.

A spring 31 is forced against a pin 32 as in the form above described for biasing the closing ring to move in a direction toward closing position. The spring has one end 15 extending into a socket in a screw 33 which screw engages threads in the ring 13. This ring is provided with a threaded plug 34 for closing a corresponding opening leading to the pin 32 from the opposite side and when 20 the direction of operation of the cutter-head is to be changed the positions of the threaded plugs 33 and 34 may be exchanged, the spring 31 being moved with the plug 33 whereby it biases the ring 14 toward a closing 25 position the opposite to that illustrated in the drawings.

I have illustrated and described a form of the invention which is the one at present preferred but it will be obvious to those skilled in the art that numerous changes 30 may be made in my device and therefore I do not limit myself to what is shown in the drawings and described in the specification but only as indicated in the appended 35 claims, it being conceivable that the relative rotation of parts might be reversed, the position and form of the locking detents might be altered, and many other changes might be made.

Having thus fully described my said invention, what I claim as new and desire to secure by Letters Patent is:

1. A die head comprising a ring mounted co-axially with the head and adapted to 45 oscillate relatively thereto for opening and closing the head, one or more pins movable lengthwise of the head from a position back of the rear face of the ring into engagement with said ring for holding it in head-closing 50 position, and means permitting the pins to advance toward such position even after the ring is rotated past its normal locking position, substantially as set forth.

2. A die head comprising means movable 55 in a path concentric with the axis of the head for opening and closing the head, a spring for moving said means in one direction, one or more pins movable lengthwise of the head from a position out of engagement with said means into a position for holding 60 said means in head-closing position, and means permitting said pins to assume locking position in an over-travel position of said means past such head-closing position, substantially as set forth.

3. A die head comprising tangential thread cutting chasers, a ring at the front end of the frame connected to the said chasers and movable about the axis of the die head for opening and closing the head, 70 one or more pins movable lengthwise of the head into engagement with recesses in the ring, bushings in said recesses adapted to fit about the ends of said pins, and shallow recesses in the ring at one side of said 75 bushings the bushings being cut away at that side to the depth of said shallow recesses, substantially as set forth.

4. A die head comprising means movable either clockwise or counter-clockwise for 80 locking the head closed to cut right-hand and left-hand threads respectively, means for locking the ring in head closing position, and resilient means to return said movable means to predetermined position after 85 an over-travel of the same in either direction, substantially as set forth.

5. A die head comprising means movable either clockwise or counter-clockwise for locking the head closed to cut right-hand and left-hand threads respectively, means for locking the ring in head closing position, means to return said movable means to predetermined position after an over-travel 90 of the same in either direction, and means 95 permitting said locking means to move toward locking position on such over-travel, substantially as set forth.

6. A die head comprising means movable either clockwise or counter-clockwise for 100 locking the head closed to cut right-hand and left-hand threads respectively, means for locking said movable means in head-closing position including one or more pins 105 movable lengthwise of the head to engage recesses in said movable means, and means adaptable to return the head to a predetermined position after an over-travel of the movable means in either direction, substantially as set forth.

7. A die head comprising means movable either clockwise or counter-clockwise for locking the head closed to cut right-hand and left-hand threads respectively, means for locking said movable means in head-closing position including one or more pins 115 movable lengthwise of the head to engage recesses in said movable means, means adaptable to return the head to a predetermined position after an over-travel of the movable 120 means in either direction, and means permitting the locking means to move toward locking position on such over-travel, substantially as set forth.

8. A thread-cutting die head comprising tangential chasers, a ring movable either clockwise or counter-clockwise about the head for locking the head closed to cut right-hand and left-hand threads respectively, one or more pins 125 movably mounted 130

on the head, and a pair of apertures in the ring adjacent each pin adapted to receive the pins to lock the head in right-hand or left-hand cutting position respectively, substantially as set forth.

9. A die head comprising a ring adapted to move clockwise or counter-clockwise about the head for closing the head to cut right-hand or left-hand respectively, a ring held in fixed relation to said axis, one or more locking pins on one of said rings, and twin recesses on the other ring for each of said pins whereby the head may be locked in either of said closed positions, substantially as set forth.

10. A die head comprising tangential thread-cutting chasers, means movable either clockwise or counter-clockwise for locking the head closed to cut right-hand and left-hand threads respectively, means for locking the ring in head-closing position including a pair of apertures in the ring adjacent each pin adapted to receive the pins to lock the head in right-hand or left-hand cutting position respectively, and means permitting over-travel of the ring about the head in its movement toward either closed position, substantially as set forth.

11. A cutter head comprising a closing ring adapted for cooperation with right-hand and left-hand cutters to lock the head in closed relation, one or more pins movable longitudinally of the head, a pair of recesses on the ring adjacent each pin, and bushings in said recesses said bushings being reduced in height at their adjacent sides to permit over-travel of the ring about the head in its movement toward either closed position, substantially as set forth.

12. A die head comprising chasers, supporting means therefor, means relatively rotatable to right or left about the head for closing the head to cut to right or left hand respectively, means to lock the head closed in either position including one or more detents on one of said relatively rotatable members, said detents being mov-

able lengthwise of the head, and twin recesses in the other movable member for each one of said detents, substantially as set forth.

13. A die head comprising chasers, supporting means therefor, means relatively rotatable to right or left about the head for closing the head to cut to right or left hand respectively, means to lock the head closed in either position including one or more detents on one of said relatively rotatable members, twin recesses in the other for each detent, and means permitting said detents to advance on over-travel of said relatively rotatable members, substantially as set forth.

14. A die head comprising chasers with their bodies extending tangentially to the work, supporting means for said chasers, a ring rotatable relatively to the head for moving the chasers into and out of closed position, blunt-ended pins on one of the relatively rotatable parts adapted to engage or disengage recesses in the other for locking the head in closed position when engaged, and means permitting the locking means to advance on over-travel of the relatively rotatable parts when disengaged, substantially as set forth.

15. A die head comprising elongated chasers having serrations on a long face tangential to the work, a control member arranged to oscillate about the axis of the head in a plane substantially at right angles to said axis, means on the control member whereby the same may be oscillated relatively to the head, and locking means movable axially relatively to the control member from a position out of engagement with said control member to a position of engagement therewith on overtravel of said control member, substantially as set forth.

In witness whereof, I have hereunto set my hand at Waynesboro, Pennsylvania this seventeenth day of October, A. D. nineteen hundred and twenty-four.

HARRY T. SHEARER.
